UNITED STATES PATENT OFFICE.

ROY G. SANDS, OF WAUKEGAN, ILLINOIS, ASSIGNEE TO COOK ELECTRIC COMPANY,
OF CHICAGO, ILLINOIS, A CORPORATION OF ILLINOIS.

RENEWABLE ELECTRIC FUSE.

Application filed June 3, 1920. Serial No. 386,208.

To all whom it may concern:

Be it known that I, ROY GRANVILLE SANDS, a citizen of the United States, residing at Waukegan, in the county of Lake and State of Illinois, have invented new and useful Improvements in Renewable Electric Fuses, of which the following is a full, clear, concise, and exact description, reference being had to the accompanying drawing, 10 forming a part of this specification.

My invention relates to electric fuses and it has special reference to that type of electric fuses known as renewable fuses.

More particularly my invention pertains 15 to a fuse of the type indicated above which embodies means for insuring, under all conditions of operations, complete electrical contact between a renewable fusible link and the permanent members associated therewith 20 which comprise the fuse.

An object of my invention is to provide a renewable fuse of the character designated which may be readily assembled and which embodies a fusible element that may be conveniently replaced without requiring any 25 new parts or members, with the exception of the fusible element.

Another object of my invention is to provide a fuse which will be economical to 30 construct and which embodies in its structure very few permanent parts, none of which is subject to rapid deterioration or requires replacement when the fusible element is being renewed.

35 For a better understanding of my invention, reference may be had to the following description and the accompanying drawings, in which:

Fig. 1 represents a side view of an electric fuse, partly assembled, that is constructed in accordance with my invention;

Fig. 2 is a view, partially in elevation and partially in section, of the upper portion of the fuse of Fig. 1;

Fig. 3 is a plan view taken along the sectional line 3—3 of Fig. 2;

Fig. 4 is a perspective view showing one of the washers that comprises a permanent member of my renewable electric fuse;

Fig. 5 is a view in perspective of a fusible element that may be embodied in the renewable electric fuses of my present invention;

Fig. 6 is a side view of a modified form of my invention;

Fig. 7 is a view, partially in elevation and partially in section, of the fuse illustrated in Fig. 6;

Fig. 8 is a plan view of the electric fuse illustrated in Fig. 7; and

Fig. 9 is a perspective view of the washer incorporated in the electric fuse illustrated in Figs. 6, 7 and 8.

Attention is first directed to the renewable electric fuse illustrated in Figs. 1 to 5 inclusive wherein the tubular casing 1, made of electrical insulating material, such as fibre, is adapted to be provided at both of its ends with metallic caps or ferrules 2, only one being shown. Supported by each of the caps 2 is an electrical terminal member 3 which, in this instance, comprises a flat portion 4 having an integrally formed and up-standing knife-blade portion 5. The two ends of the insulating tubular shell 1 are exteriorly threaded in the manner indicated at 6. The metallic caps 2 are interiorly threaded so as to engage the screw threads 6. The metallic caps 2 are cup-shaped and are severally provided with a central opening 7.

As illustrated in Figs. 2 and 3, the upper edge or rim 8 of the tubular member 1 is provided with opposed spaced notches in which projections 9 and 10, formed on a washer 11, are received.

The flat portion 4 of the knife blade terminal member 3 is circular with the exception of two opposed and spaced projections 12 and 13 which have the same widths respectively as the projections 9 and 10 formed on the washer 11. The washer 11, shown enlarged in Fig. 4, is preferably provided with a rectangular body portion upon which the projecting portions 9 and 10 are formed. The projections 12 and 13 of the terminal member 3 are located at points corresponding to the projections 10 and 9 formed on the washer 11. When my electrical fuse is assembled, as shown in Fig. 3, the corresponding projections of the terminal member 3 and of the washer 11 are superposed and received in the notches cut in the upper edge or rim 8 of the member 1.

The fusible element 14, made of any suitable material such as a zinc alloy, is provided with restricted portions 15 and 16, the portion 15 being intermediate the portions 16. The end portions of the fusible element 14 are provided with longitudinally extending slots 17. In assembling the renewable

electric fuse of my invention, the fusible element 14 has one only of its ends bent over as shown at 18 in Fig. 5. The projection 10 formed on the metallic washer 11 is extended 5 through the slot 17, the washer 11 engaging the bent-over end 18 of the fusible element on its under side. In this position the bent-over end 18 extends longitudinally of the washer 11 and engages it on its outer surface. The bent-over end 18 may be provided 10 with an outer contour which coincides generally with that of the washer 11 excepting for the projections 9 and 10 formed on the washer.

15 The slot 17 provided in the bent-over end 18 extends beyond a threaded opening 19 formed in the washer 11. The washer 11 engages the fusible link element 14 as explained above and is then positioned relative 20 to the insulating casing 1 so that the fusible element 14 extends therethrough. The washer 11 is properly positioned by reason of the projections 9 and 10 being received in the proper notches cut in the rim 8 of the insulating casing 1. The metallic cap 2 in which the terminal member 3 is received is then screwed upon the end of the casing 1 in such fashion that the bent-over end 18 of the fusible link 14 is held intermediate the 25 underside of the flat portion 4 of the terminal member 3 and the upper face of the washer 11.

Moreover, the projections 12 and 13 formed on the terminal member 3 are positioned 30 so as to be received in the proper notches cut in the rim 8 of the casing 1. By firmly screwing the cap 2 to the threaded end of the insulating casing 1, the bent-over end 18 of the fusible element may be retained 35 in close contact with both the terminal members 3 and the washer 11. However, to ensure permanent and good electrical contact under all conditions a screw 20 may be provided which extends through the flat portion 4 of the terminal member 3, the slot 17 formed in the bent-over end 18 of the fusible element 14 and the threaded opening 19 formed in the washer 11. By tightening the screw 20 it will be observed that the three 40 electrical conducting members of the fuse, namely, the terminal member 3, the fusible element 14 and the metallic washer 11 are permanently maintained in close electrical contact even though the cap member 2 becomes 45 loosened upon the shell or casing 1. The screw 20 serves to retain this electrical connection intact. It is also to be observed that the screw 20 will tend to retain the knife blade terminal 5 in a fixed position 50 upon the insulating shell 1 when the electric fuse is being inserted in the fuse clips. It is known that when inserting ordinary electric fuses in the retaining fuse clips the pressure exerted by the clips tends to displace 55 the knife blade terminal from the associated

shell or casing. By permanently securing together the washer 11, the fusible link 14 and the terminal member 3 by means of the screw 20, the knife blade members 5 of the fuse will not tend to become loosened.

70 After the fuse has been assembled as shown in Fig. 2, corresponding elements may be placed in position at the other end of the casing 1. This is effected by bending over the straight end of the fusible link 14 75 as shown by the bent-over end 21 of Fig. 5. The washer 11 and the terminal member 3, similar to those at the upper end of the fuse, may then be placed in position with the bent-over end 21 of the fusible element 14 between 80 them. A cap 2 and a screw 20 will then be threaded in position so that both ends of the electric fuse will be identical.

85 The modified form of my electric fuse illustrated in Figs. 6 to 9 inclusive, is very similar to the electric fuse described above. In this instance, however, a terminal structure in the form of a cap member 22 of a common form of construction is provided. The fusible element may be similar to that 90 illustrated in Fig. 5 and the bent-over ends of this fusible element may be engaged by washers 23 that are similar to the washer 11.

95 The cap 22, in this instance, is provided with an integrally formed face 24 having a central opening through which the screw 20 may be inserted. The screw 20, in this instance, is centrally positioned upon the cap 22 and is threaded into an opening 25 formed in the washer 23. It will be noted 100 that the bent-over ends of the fusible element 14 are placed intermediate the washer 23 and the flat face 24 formed on the metallic cap member 22. The screw 20 which projects through these three metallic elements 105 ensures a good electrical contact at all times.

110 When refilling the fuses herein described it is necessary only to remove the caps 2 and 22 as well as the screws 20. This permits the fusible link 14 to be readily replaced by a new one. It will be noted that the permanent members of my renewable fuse are few 115 in number and that their combination provides a very rigid structure. Moreover, the screw 20 ensures good electrical contact at 115 all times between the parts designed to carry the electric current. The insulating casing 1 is adapted for continuous use and does not deteriorate under repeated ruptures of the fusible link 14 contained therein.

120 While I have described in detail several embodiments of my invention it is to be understood that I desire only such limitations to be imposed thereon as are set forth in the appended claims.

125 Having thus described my invention, what I claim as new and desire to secure by Letters Patent is:

1. An enclosed renewable fuse comprising a tubular container, a knife blade terminal 130

- member having a flat portion covering the end of said tubular container, a washer beneath said flat portion, said flat portion and said washer being provided with superposed lugs engaging said container, a fuse link having a bent-over end retained between said flat portion and said washer, and means for retaining said flat portion on said container.
- 10 2. An enclosed renewable fuse comprising a tubular container, a knife blade terminal member having a flat portion covering the end of said tubular container, a washer beneath said flat portion, a fuse link having a bent-over end retained between said flat portion and said washer, a ferrule independent of said terminal member for retaining said flat portion on said container, and retaining means extending from said flat portion through said fuse link and into said washer.
- 15 3. An inclosed renewable fuse comprising a tubular container, a knife blade terminal member having a flat portion covering the end of said tubular container, a washer beneath said flat portion, said flat portion and said washer being provided with superposed lugs engaging said container, a fuse link having a bent-over end retained between said flat portion and said washer, said bent-over end being provided with an opening through which the lug on said washer passes, and means for retaining said flat portion on said container.
- 20 4. An enclosed renewable fuse comprising a tubular container, an end cap therefor, a washer contained in said end cap, said washer having a lug engaging the end of said container, and a fuse link in said container having a bent-over end positioned over said washer in said end cap, said bent-over end being provided with an elongated opening through which said lug extends.
- 25 5. An enclosed renewable fuse comprising a tubular container, end cap means therefor, a washer contained in said end cap, said washer having a lug engaging the end of said container, a fuse link in said container having a bent-over end positioned over said washer in said end cap means, and retaining means extending from said end cap means through said bent-over end and into said washer, said bent-over end being provided with an elongated opening through which said retaining means and said lug extend.
- 30 6. In an electric fuse, a washer member having a lug extending from its periphery, and a fuse link having an end bent over the periphery of said washer member and over a face thereof, said end having an opening therein through which said lug passes.
- 35 7. In an electric fuse, a washer member having a lug extending from its periphery, a fuse link having an end bent over a face of said washer member, and means for retaining said end upon the face of said washer, said end being formed with an elongated slot through which said lug and said means pass.

In witness whereof, I have hereunto subscribed my name.

ROY G. SANDS.
